UNITED STATES PATENT OFFICE.

EMIL BUBLITZ, OF IRVINGTON, NEW JERSEY.

COMBINED ANTIRATTLING SAFETY-LOCK AND VENTILATING DEVICE FOR WINDOWS.

1,295,426.

Specification of Letters Patent. Patented Feb. 25, 1919.

Application filed August 2, 1917. Serial No. 184,040.

To all whom it may concern:

Be it known that I, EMIL BUBLITZ, a subject of the Emperor of Germany, but have made application for citizenship of the 5 United States, residing at Irvington, in the county of Essex and State of New Jersey, have invented certain new and useful Improvements in Combined Antirattling Safety-Lock and Ventilating Devices for 10 Windows; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in anti-rattling and tightening 20 devices for windows; and, the present invention has reference, more particularly, to a novel means adapted to be attached to and coöperating with the sashes of a window, to provide a combined anti-rattling and 25 safety device, applicable to windows of various construction, the device serving also as a combined safety-lock and ventilating means, to permit either or both of the window sashes to be respectively raised or lowered to their full extent, or to permit a limited 30 movement of either or both of the window sashes for ventilating purposes, and to lock the window sashes, in that case, against further movement, so that it will be impossible 35 for a person to enter from the outside of the window, or to manipulate the combined anti-rattling means and safety-attachment from the outside in the endeavor to raise or lower the window sashes a distance 40 sufficient to permit entrance into the room through the window.

The invention, therefore, has for its principal object to provide a novel, simple and cheaply constructed, as well as efficiently 45 operating attachment or device for the purposes herein-above stated, which provides a combined anti-rattling and wind-proof safety-lock, as well as a ventilating means, comprising but a very few parts, and being 50 readily attached in its operative position with relation to the respective window sashes, without interference to the lowering or raising of the window sashes to their fullest extent, or to a limited degree, either

at the top or bottom, at both ends of the window, for ventilation.

Other objects of the present invention not at this time more particularly enumerated will be clearly understood from the following detailed description of the present invention.

With the various objects of the present invention in view, the said invention consists, primarily, in the combined anti-rattling and wind-proof safety-lock and ventilating means for windows hereinafter set forth; and, the invention consists, furthermore, in the novel arrangements and combinations of the various devices and parts, as well as in the details of the construction of the said parts, all of which will be more fully described in the following specification, and then finally embodied in the clauses of the claim which are appended to and which form an essential part of the said specification.

The invention is clearly illustrated in the accompanying drawings, in which:—

Figure 1 is an inner face view of a window frame and its window sashes, showing the upper sash locked by means of the mechanism embodying the principles of the present invention in a partly lowered position; and Fig. 2 is a horizontal sectional representation of the same, said section being represented as taken on line 2—2 in said Fig. 1, and said view being made on an enlarged scale.

Figs. 3 and 4 are transverse vertical sectional representations of the window frame and window sashes, showing in the respective views, and in operative coöperation with the upper and lower window sashes, and in its locked and unlocked relation with the window sashes, the combined anti-rattling and wind-proof safety lock and ventilating means.

Fig. 5 is a detail view, in side elevation, of a portion of a window-frame and one of the controlling or operating levers of the combined anti-rattling and wind-proof safety-lock and ventilating means provided with an auxiliary locking means for retaining the lever in its position against movement, when the combined safety-lock and ventilating means has been operated.

Similar characters of reference are employed in the said above described views, to indicate corresponding parts.

Referring now to the said drawings, the reference-character 1 indicates any usual construction of window-frame in which are slidably disposed between the usual stiles 2 5 and 3 and the stop-beads 4, the upper window sash 5 and the lower window sash 6, the said stiles and beads being secured in any suitable and usual manner upon the faces of side-members 7 of the window frame. As 10 shown, the vertically disposed stiles 3 are channeled or grooved, as at 8, and the stop-beads 4 are similarly channeled or grooved, as at 9. Likewise, at the central portions of the side-members 7, in alignment with the 15 lower meeting rail 10 of the upper sash 5 and the upper meeting rail 11 of the lower sash 6, when both sashes are closed, the said side-members 7 are provided with the horizontally disposed and rearwardly extending 20 channels or grooves 12. Pivotaly mounted upon suitably disposed pivots 13, as nails, screws, pins, or the like, are oscillatory levers or arms 14, each arm thus being movably disposed in a channel or groove 12 and having 25 a portion extending from said channel or groove 12 and being provided with a suitable finger-piece, as 15. Extending from each lever or arm 14 is a pivot-pin 16 upon which is loosely mounted a downwardly extending binding or presser-plate 17, said plates being movably disposed in the channels or grooves 9 of the beads 4 and having right-angled portions or flanges 18 adapted to be brought into frictional binding or 30 pressing engagement with the faces of the vertical rails 19 of the lower window sash in the manner and for the purposes herein- 35 after more fully stated.

As shown in Figs. 3 and 4 of the drawings, 40 the said binding or presser-plates 17 are also provided with angularly disposed elongated slots or openings, as 20, into which extend correspondingly placed pins or screws 21 with which the side-members 7 of the window-frame are provided. Each lever or 45 arm 14 is also provided with another pivot-pin, as 22, upon which is also loosely mounted an upwardly extending binding or presser-plate 23, said plates being movably 50 disposed in the channels or grooves 8 of the stiles 3 and having right-angled portions or flanges 24 adapted to be brought into frictional binding or pressing engagement with the vertical rails 25 of the upper window 55 sash in the manner and for the purposes hereinafter more fully stated.

As indicated in dotted outline in Figs. 3 and 4 of the drawings, the said binding or presser-plates 23 are also provided with angularly disposed elongated slots or openings, as 26, into which extend correspondingly placed pins or screws 27 with which the side-members 7 of the window-frame are also provided.

When the several devices and parts of the 65 herein-before described combined safety-lock and ventilating means are in their relative positions indicated in Figs. 2 and 3 of the drawings, it will be seen from an inspection of said figures, that the binding or 70 pressing portions or flanges 18 and 24 of the respective plates 17 and 23 are out of frictional retaining contact with the respective side-rails 19 and 25 of the lower and upper window-sashes, so that either or both of said 75 sashes can be moved up or down to be brought into their opened or closed positions within the window frame, as will be evident. When, however, the said arms or levers 14 are moved from their positions indicated in 80 Fig. 3 of the drawings to the positions shown in Fig. 4, then the fulcrumal arrangement of said arms or levers 14 upon the pivot-pins 13 will cause the plates 17 to slide upwardly upon the pins 21, thereby bringing their 85 binding or pressing portions or flanges 18 into firm holding or retaining engagement with the inner faces of the side-rails 19 of the lower window sash and pressing the outer face-portions of said side-rails into frictional retaining engagement with the corresponding face-portions of the stiles 2. Simultaneously, the said arms or levers 14 will cause the plates 23 to slide downwardly 90 upon the pins 27, thereby bringing their 95 binding or pressing portions or flanges 24 into firm holding or retaining engagement with the outer faces of the side-rails 25 of the upper window sash and pressing the inner face-portions of said side-rails into 100 frictional holding or retaining engagement with the corresponding face-portions of the stiles 2. Thus, both window sashes whether 105 previously opened, or whether in their closed positions will be securely held or locked against movement, until the parts of the mechanism have again been moved in their relative positions indicated in Fig. 3 of the drawings.

The arrangement of the devices and parts 110 of the safety-lock and ventilating means is such that either or both window-sashes can be opened wide, or can be raised or lowered to a limited degree only, for ventilation, without danger of objectionable persons entering the room through the opened window. Furthermore, when both window sashes are closed, they can be positively locked by means of the mechanism, any rattling of the window sashes in the frame being prevented, 115 and also all joints between the sashes and the stiles 2, and the joint between the meeting rails 10 and 11 of the lower and upper window sashes will be brought into such tight contact, so that a perfect and positively 120 wind-proof window is the result.

To guard against accidental movement of the arms or levers 14 when brought into

the positions indicated in Fig. 4 of the drawings, an auxiliary locking device or means such as is shown in Fig. 5 may be employed, although any other suitable locking means may be used, if desired.

The locking means here represented in said Fig. 5 consists, essentially, of an arrangement of racks 28, attached by means of pins or screws 29 upon the inwardly exposed face-portions of the beads 4, each arm or lever 14 being provided near its finger-piece 15 with a pivot-pin 30. Engagement of suitable holding dogs, as 31, which are pivotally mounted upon said pins 30, with the teeth of the racks 28 is caused by an arrangement of suitable springs, as 32, as will be evident.

The arrangement of these parts permits of the upward movements of the arms or levers 14, and positively retains said arms or levers against accidental movement from their raised positions.

To disengage the holding dogs from the teeth of the racks, when it is desired to lower the said arms or levers 14, each dog 31 has a projection or extension, as 33, which serves as a fingerpiece for the withdrawal of the holding dogs from the racks, simultaneously with lowering operations of the said arms or levers 14 by means of their fingerpieces 15.

I am aware that some changes may be made in the general arrangements and combinations of the several parts, as well as in the details of the construction of the said parts, without departing from the scope of the present invention, as set forth in the foregoing specification and as defined in the clauses of the claim which are appended thereto. Hence, I do not limit my invention to the exact arrangements and combinations of the parts as described in the said specification, nor do I confine myself to the exact details of the construction of

the said parts as illustrated in the accompanying drawings.

I claim:—

1. A combined anti-rattling safety-lock and ventilating device for windows comprising a pair of vertically placed presser-
50 plates having angularly disposed elongated openings, pins projecting from a side-member of a window-frame, said pins extending into said openings whereby said plates are movably disposed upon said side-member of
55 the window-frame, each plate having a flange adapted to be brought into frictional retaining engagement with a window sash to provide a binding action of the window sash in the window-frame so as to prevent
60 rattling, and means connected with said plates for actuating said plates simultaneously in opposite directions.

2. A combined anti-rattling safety-lock and ventilating device for windows comprising a pair of vertically placed presser-
65 plates having angularly disposed elongated openings, pins projecting from a side-member of a window-frame, said pins extending into said openings whereby said plates are
70 movably disposed upon said side-member of the window-frame, each plate having a flange adapted to be brought into frictional retaining engagement with a window sash to provide a binding action of the window sash in the window-frame so as to prevent
75 rattling, and an operating lever pivotally mounted upon said side-member of the window-frame and also pivotally connected with each plate for actuating said plates
80 simultaneously in opposite directions.

In testimony that I claim the invention set forth above I have hereunto set my hand this 27th day of July, 1917.

EMIL BUBLITZ.
